Primary Examiner — Paula Allen Greene*(74) Attorney, Agent, or Firm* — Michael Best & Friedrich LLP(57) **CLAIM**

The ornamental design for a loudspeaker accessory tray, as shown and described.

DESCRIPTION

FIG. 1 is a front, top, right perspective view of a loudspeaker accessory tray according to the present invention;
FIG. 2 is a rear, top, right perspective view thereof;
FIG. 3 is a right side elevation view thereof;
FIG. 4 is a left side elevation view thereof;
FIG. 5 is a front elevation view thereof;
FIG. 6 is a rear elevation view thereof;
FIG. 7 is a top plan view thereof;
FIG. 8 is a bottom view thereof; and,
FIG. 9 is a front, top, right perspective view thereof as mounted to the top of a loudspeaker.
The dashed lines illustrate portions of the loudspeaker accessory tray, and also environment in FIG. 9, that form no part of the claimed design. The dash-dot-dash lines of FIGS. 1, 2, 7, and 9 illustrate a boundary of the claimed design and form no part of the claimed design.

1 Claim, 7 Drawing Sheets---
